Primary Examiner — Nicole C Shiflet*Assistant Examiner* — Karen M. Jones(74) *Attorney, Agent, or Firm* — Carlson, Gaskey & Olds, P.C.(57) **CLAIM**

The ornamental design for a heart shaped loom, as shown and described.

DESCRIPTION

FIG. 1 is a perspective view of the heart shaped loom.

FIG. 2 is a front view of the heart shaped loom.

FIG. 3 is a back view of the heart shaped loom.

FIG. 4 is a first side view of the heart shaped loom.

FIG. 5 is a second view of the heart shaped loom.

FIG. 6 is a top view of the heart shaped loom; and,

FIG. 7 is a bottom view of the heart shaped loom. The broken lines in the drawings depict portions of the heart shaped loom that form no part of the claimed design.
